DISPENSING CARTON WITH HINGED COVER

Frank L. Broeren, Neenah, Wis., assignor to
 Marathon Paper Mills Company, Rothschild,
 Wis., a corporation of Wisconsin

Application April 28, 1941, Serial No. 390,846

4 Claims. (Cl. 206—58)

This invention relates to a dispensing carton having a hinged cover formed from an integral blank of cardboard and the like. More specifically, this invention relates to a dispensing carton for containing a roll of waxed paper from which the paper is dispensed in web form and torn off in suitable lengths as needed.

Generally speaking, the present invention contemplates a carton construction for dispensing or removing any article contained therein which can be grasped by the fingers by opening a hinged cover. The carton is preferably formed from an integral blank which is suitably cut and scored to provide a container having front, rear, bottom and end walls and a cover integrally hinged to the container along a hinge of a novel construction. By virtue of this construction, the hinge is extremely flexible and facilitates easy opening of the cover. Also when the cover is released it has a tendency to fall back to closed position. To obtain this flexibility, the hinge is alternately scored and cut along the hinge line to any desired ratio of respective lengths of the cut and scored portions.

Other further details of the invention will be apparent from the following specification and appended drawings.

Referring to the drawings,

Figure 1 is a perspective view of the dispensing carton made in accordance with the present invention showing the cover in closed and locked position.

Figure 2 is a perspective view of the dispensing carton showing the operation of tearing a length of paper web dispensed therefrom.

Figure 3 is a perspective view of the carton showing the hinged cover in open position.

Figure 4 is a plan view of the closed carton.

Figure 5 is an enlarged fragmental sectional view taken along lines 5—5 of Figure 3.

Figure 6 is a fragmental plan view of a modification of the carton construction, and

Figure 7 is a fragmental sectional view taken on lines 7—7 of Figure 6.

Referring to the drawings, the carton 10 is preferably made from a single integral blank of cardboard and the like which is suitably cut, scored and glued to provide a front wall 13, a rear wall 2, end walls 3, a bottom wall and a top panel 4. A cover 11 is integrally hinged to the top panel 4 along the hinge designated by numeral 12. The cover may be provided with a suitable cutting blade 9 affixed to the free edge thereof for facilitating tearing the free end of a web 20 from a roll of paper contained within

the carton. The front wall of the carton may be provided with a perforated score line 5 and an inverted U-shaped cut line 6. The cover is provided with a cut score line 7 which forms a tongue portion that is insertable through the cut score line 6 into locking engagement as illustrated in Figure 1, thereby locking the cover when the carton is not in use. If desired, a portion of the front wall 13 may be removed along the score line 5 when the carton is to be used for facilitating insertion of the thumb within the carton for contacting the roll or other article contained therein. The construction of the carton so far described is fully disclosed in copending application Serial No. 370,388, filed December 16, 1940.

An important feature of the present invention resides in providing a hinge 12 for the cover of a novel construction which consists in forming the hinge from alternate cut and creased portions which are connected to each other. Referring to Figures 3 and 4, a hinge is provided having equally spaced semi-circular, curvilinear, triangular, or other suitably contoured cut portions indicated by numeral 15, so that an area is outlined extending beyond the hinge line defined by the straight creased score lines. These cut portions are connected by the spaced creased score lines 14 which in the conventional hinge would be a continuous score line. Each of the ends of the hinge line is also preferably cut as indicated by numerals 16 for a substantial distance to give greater flexibility to the hinge. The alternate cut and creased portions of the hinge 35 may be of any desired ratio of lengths so as to decrease the length of the creased portion of the hinge.

Hitherto, it has been customary to utilize merely a continuous creased score line for the hinge. Obviously, when using a thick cardboard stock, hinging on such a continuous long creased score line is resisted by the inherent stiffness of the carton stock. The cover can not, therefore, be readily opened and fully closed as the flexibility 45 of the hinge is very limited. Furthermore, when a continuous creased hinge line is utilized of any substantial length, there is a tendency for the hinge to bulge outwardly when the cover is opened, thereby further decreasing flexibility of the hinge.

These disadvantages are entirely obviated by the present invention which provides an extremely flexible hinge for the cover. By providing cut or slit portions in the hinge, the total length of the creased score portion on which hinging of

the cover takes place is greatly reduced so that the resistance to flexing of the carton stock is greatly reduced, thereby providing greater flexibility in hinging the cover. Furthermore, the present hinge construction permits the opened cover upon release to fall back readily into closed position as compared with the previous full line creased hinge which after opening resists closing because the fibers at the hinge must be reversely bent to their former position.

Various modifications may be made in actual carton constructions utilizing the present concept. The invention is not limited to any definite contour of the cut and creased portions of the hinge line. For example, Figures 6 and 7 illustrate a modification of the hinge line wherein the cut portions 15 are reversely positioned in relation to each other and are connected by creased portions 14. Each of the ends of the hinge line is preferably cut for a substantial length as indicated by numeral 16 to provide still further flexibility of the hinge.

It is to be understood that the hinge construction is not necessarily limited to the specific carton construction herein disclosed. It may be utilized on any type of carton construction having a hinged cover therefor. The cover, for example, may be integrally hinged to any portion of an open ended container such as to the front or rear walls thereof, but the principle of hinged construction is utilized in a similar relation as in the specific embodiment herein disclosed. It is, therefore, intended to claim the invention herein disclosed as broadly as defined in the appended claims.

I claim:

1. A dispensing carton for receiving a roll of sheet material comprising a blank suitably scored and cut to provide a front, rear, bottom, end and top panels, said top panel having an integral portion hinged along a longitudinal line extending from one end of the panel to the other, said portion functioning as a cover portion, said hinge comprising regularly spaced cut curvilinear score lines and creased score lines connecting said cut score lines and said hinge being cut at each end thereof for a substantial length along a continuous substantially zig-zag cut line extending at an acute angle at one portion thereof beyond said hinge line, and then in reverse direction at an acute angle to said hinge line.

2. A dispensing carton comprising a blank suitably scored and cut to provide a front, rear,

bottom, end and top panels, said top panel having an integral portion hinged along a longitudinal line extending from one end of the panel to the other, said portion functioning as a cover portion, said hinge comprising regularly spaced continuous cut and creased score lines, said cut lines intersecting said creased lines along convergent lines and at an acute angle to said creased lines so as to provide cut tongue portions extending beyond said creased lines whereby upon hinging said cover open the fibers of said blank will be instantly separated without substantial frictional engagement at the cut portions.

3. A dispensing carton comprising a blank suitably scored and cut to provide a front, rear, bottom, end and top panels, said top panel having an integral portion hinged along a longitudinal line extending from one end of the panel to the other, said portion functioning as a cover portion, said hinge comprising regularly spaced continuous cut and creased score lines, said cut lines intersecting said creased lines along convergent lines and at an acute angle to said creased lines so as to provide cut tongue portions extending beyond said creased lines whereby upon hinging said cover open the fibers of said blank will be instantly separated without substantial frictional engagement at the cut portions and said hinge being cut at each end thereof for a substantial length along a continuous substantially zig-zag cut line extending at an acute angle at one portion thereof beyond said hinge line, and then in reverse direction at an acute angle to said hinge line.

4. A dispensing carton comprising a blank suitably scored and cut to provide a front, rear, bottom, end and top panels, said top panel having an integral portion hinged along a longitudinal line extending from one end of the panel to the other, said portion functioning as a cover portion, said hinge comprising continuous alternately arranged semi-circular cuts and creased score lines, said cut lines intersecting said creased lines along convergent lines and at an acute angle to said creased lines so as to provide cut tongue portions extending beyond said creased lines whereby upon hinging said cover open the fibers of said blank will be instantly separated without substantial frictional engagement at the cut portions.

FRANK L. BROEREN.
